UNITED STATES PATENT OFFICE.

CHARLES M. CLARKE, OF PITTSBURG, PENNSYLVANIA, ASSIGNOR TO HEBB COKE DRAWER COMPANY, OF UNIONTOWN, PENNSYLVANIA, A CORPORATION OF PENNSYLVANIA.

COKE-DRAWING APPARATUS.

No. 923,139.

Specification of Letters Patent.

Patented June 1, 1909.

Application filed April 20, 1904, Serial No. 204,034. Renewed October 21, 1908. Serial No. 458,885.

To all whom it may concern:

Be it known that I, CHARLES M. CLARKE, a citizen of the United States, residing at Pittsburgh, in the county of Allegheny and State of Pennsylvania, have invented certain new and useful Improvements in Coke-Drawing Apparatus, of which the following is a specification, reference being had therein to the accompanying drawing, forming part 10 of this specification, in which—

Figure 1 is a longitudinal sectional view of a coke drawing machine embodying my improved rake beam. Fig. 2 is a longitudinal vertical sectional view of my improved rake beam for coke drawing apparatus, partly broken away. Fig. 3 is a plan view of the rear end of the beam showing the cylinder for reciprocating the rake. Fig. 4 is a partial sectional view similar to Fig. 1, showing 20 the top of the rake thrown outwardly. Fig. 5 is a similar view showing the rake folded up underneath the beam in the position assumed in entering the oven. Fig. 6 is a horizontal sectional view on the line 25 VI. VI. of Fig. 5. Fig. 7 is a cross sectional view on an enlarged scale through the beam and its driving pinion, indicated by the line VII. VII. of Fig. 1. Fig. 8 is a cross sectional view on an enlarged scale through the 30 front end of the beam, taken on the line VIII. VIII. of Fig. 2, the slide bar having been removed. Fig. 9 is a detail view showing a modification.

My invention relates to apparatus for 35 drawing coke from the oven, wherein a traveling structure is provided with a reciprocating beam having a rake or scraper head adapted to be extended into and withdrawn from the oven to empty the contents 40 therefrom.

The present application refers more particularly to the construction of the beam carrying the scraper and to the means for imparting movement to the scraper independent of the beam, or when the beam is stationary, and for positively extending or unfolding the scraper to operative position without a spring or its equivalent.

The invention is particularly adapted for 50 use with that class of apparatus shown and described in the various patents issued to John A. Hebb, typical examples of which are embodied in U. S. Letters Patent Nos. 727790, 727942, 728101, 728102, and 749058.

55 For the purpose of explaining the manner

in which the rake beam is extended into and withdrawn from the oven, raised and lowered, adjusted laterally at varying angles to reach varying portions of the oven on the same horizontal plane, or bodily transported 60 from one oven to another of a series, reference may be had to the above numbered patents. As the apparatus of the present invention, with the exception of the beam itself, the rake and its actuating mechanism, 65 is identical therewith, I shall not particularly describe the machine as a whole except such of its elements as particularly relate to the beam. It will be understood however, that the beam of this application is not limited to use with the Hebb machine, but may be incorporated with any other apparatus or combined with any other suitable operating or traveling mechanism or structure.

Referring now to the drawings, the beam 75 consists of vertical longitudinal sides 67, 67, of angle shape or other desirable structural form, connected together in any convenient manner as by bolts or rivets, or by a top plate or upper portion 68 of any suitable 80 form. Such top element, if employed, provides a good bearing for the upper bearing roller or other guiding or bearing elements of the machine. Between the sides 67 is secured a toothed rack 69 of sufficient length 85 to give the necessary in-and-out travel of the beam, with which rack the driving pinion 25 engages, by which the beam is propelled in one direction or the other through the clutch controlled driving shaft 24.

90 31 is the rake or scraper which is designed to be pivotally mounted at its top at the forward end of the beam to allow it to fold backwardly and upwardly toward the under side of the beam in entering over the top of the coke through the restricted opening of the door. The pivotal support or bearing of the top of the rake is adjustable back and forth independent of the beam, for which purpose I provide a piston 70 mounted in a cylinder 100 71, located at any convenient portion of the beam, as its back end. The cylinder is supplied at each end with steam, liquid, compressed air, or other suitable actuating medium through pipes 72, 73, connected with a controlling valve 74 mounted on the machine provided with the usual operating handle and connected with any source of supply, as a boiler 75. The pipes 72, 73, may be flexible hose or tubing or may be provided with 110

telescoping or swinging hinge joints to allow for the movement of the cylinder 71. By this means the piston and its rod 76 may be reciprocated back and forth and by connecting the piston rod 76 with the pivotal bearing of the rake 31, it will be seen that a to-and-fro movement may be imparted to its upper end. This movement is desirable for the purpose of working the relatively stationary 10 edge of the scraper down into the crevices of the coke so as to cause it to engage a section before drawing it from the oven. It will be understood that during such manipulation of the rake, a downward pressure is being exerted on the beam by means of the rollers 66 or other suitable depressing mechanism.

Any suitable actuating means for the rake may be substituted for the piston and cylinder, as for instance a solenoid magnet, or 20 movement may be imparted through a cam, crank, or lever - actuated reciprocating rod connected with the upper end of the rake, such mechanism being mounted on the beam and actuated through any mechanism which 25 may be utilized to suit the design of the machine.

In the construction shown in the principal figures of the drawings, the rake is pivotally mounted by a pin or bolt 23 in the outer end 30 of a sliding bar 77 mounted between the sides 67, which may be turned in underneath as at 78 to provide a supporting base. Cross bolts 79 may also be used, passing through longitudinal slots 80 in bar 77 and through 35 the sides, thereby providing additional bearing elements and also serving to limit the longitudinal travel of the bar, if necessary, the piston rod 76 being connected with its other end.

40 The rake is provided with a bearing shoulder 81 adapted to abut against the end of the bar when erected so as to prevent further movement and to maintain the rake in downward engagement with the coke during 45 the drawing operation. Otherwise the rake is free to fold backwardly as clearly shown in Fig. 5. Ordinarily the rake will fall to operative position by gravity, but for the purpose of positively erecting it at any position of the 50 beam, as when tilted, the bar 77 may be withdrawn, drawing the neck 82 of the rake backwardly against the front end 83 of the under plate 78, or against any other suitable abutment, thereby throwing the lower edge 55 downwardly at approximately right angles or into working position with relation to the beam.

When the rake is lowered upon the coke its upper end is then thrown outwardly and 60 backwardly somewhat rapidly, corresponding to the quick reciprocations of the beam of the Hebb patents, until it is in engagement with the coke, when outward movement is imparted to the beam and rake by pinion

25, thus drawing out the coke through the 65 door.

If desired, the upper end of the rake may be pivotally mounted by a bolt 23' passing through slots 84 in the sides 67, the piston rod being connected directly with bolt 23', 70 although I prefer the sliding bar construction as it provides additional means for erecting the rake not found in this construction.

It will be understood that I do not wish to be limited to any particular actuating, manipulating or traveling mechanism for performing the other necessary functions of an entirely operative coke drawing machine, and it is obvious that my improvement may be embodied with various constructions, 80 either mounted on ground or overhead tracks, within the province of the designing engineer.

Changes and variations may be made in the invention by the skilled mechanic, but 85 all such are to be considered as within the scope of the following claims.

I claim:—

1. A beam provided with a pivotal bearing and a rake thereon, and means for imparting movement to the pivotal bearing of 90 the rake while the beam is stationary.

2. In a coke drawing apparatus, a longitudinally reciprocating beam provided with a pivotal bearing at its front end, a vertically 95 depending rake mounted on said bearing, power actuated means mounted on the beam for imparting independent forward and backward movements to the top portion of the rake while its lower edge is in engagement 100 with the coke, and means for supplying power thereto, substantially as set forth.

3. A rake beam provided with a bearing, a rake mounted on said bearing, and means for reciprocating the bearing to and from 105 the beam to rock the rake thereon, substantially as described.

4. A longitudinally movable beam provided with a sliding bar, a rake pivotally mounted on the bar independent of the 110 beam, and means for reciprocating the bar and rake.

5. A longitudinally movable beam provided with an erecting abutment, a sliding bar, a rake pivotally mounted on the bar 115 independent of the beam, and means for reciprocating the bar and rake.

6. A longitudinally movable beam provided with a sliding bar, a rake pivotally mounted on the bar, a cylinder, a piston therein connected with the sliding bar, and valve controlled fluid connections adapted 120 to impart movement to the piston.

7. A beam provided with a longitudinally movable pivoted rake, an actuating cylinder, 125 and a piston therein connected with the rake.

8. A longitudinally movable beam pro-

vided with a sliding bar, a rake pivotally mounted on the bar, an abutment at the lower side of the beam adapted to make contact with and extend the rake, and 5 means for reciprocating the bar and rake.

9. The combination of a beam, a rake mounted on the beam for rocking movement with respect to the same, and means carried on the beam for rocking the top end 10 of the rake while the beam and the point of the rake are stationary, substantially as described.

10. A beam provided with a pivoted rake and an actuating cylinder and piston, said 15 piston being connected with the rake.

11. A traveling beam provided with a pivoted rake and an actuating motor therefor, and means for connecting said motor with a relatively stationary source of energy.

20 12. A traveling beam provided with a pivoted rake and an actuating motor mounted on the beam and connected with the rake, adapted for quick adjustment of the rake.

13. In coke drawing apparatus, the combination with a reciprocating beam and 25 means for operating it, of a rake pivoted on the beam and a double acting motor carried on the beam and adapted to be manipulated from a distance, and directly connected to 30 operate the rake independent of the motions of the beam.

14. In a coke drawing apparatus, the combination of a vertically rocking and horizontally sliding rake beam, a rake piv-

35 oted at the outer end of the beam, and motors for rocking the beam and operating the rake at the end thereof.

15. In a coke drawing apparatus, the combination of a rocking rake beam, a pressure cylinder mounted on the rear end of the 40 beam, a rake carried at the front end of the beam and movable with relation thereto, operating connections from the piston of the cylinder to the rake, and a motor for rocking the beam.

45 16. In a coke drawing apparatus, the combination of a car, a turn-table carried thereby, a vertically rocking and horizontally sliding rake beam mounted on the table, an independently adjustable rake; power actuated means for actuating the rake in opposite directions mounted on the beam, power supplying means therefor, and means for rocking and sliding the rake beam.

50 17. In a coke drawing apparatus, the combination of a car, a turn-table carried thereby, a vertically rocking and horizontally sliding rake beam mounted on the table and provided with a pivoted rake and 55 an actuating cylinder having a piston connected with the rake, and means for rocking and sliding the rake beam.

In testimony whereof I affix my signature in presence of two witnesses.

CHARLES M. CLARKE.
